WILLIAM H. ELLIOT, OF NEW YORK, AND ISAAC OSGOOD, OF UTICA,
NEW YORK.

Letters Patent No. 76,178, dated March 31, 1868.

IMPROVED APPARATUS FOR DYEING AND BLEACHING YARNS AND THREAD.

The Schedule referred to in these Letters Patent and making part of the same.

TO ALL WHOM IT MAY CONCERN:

Be it known that we, WILLIAM H. ELLIOT, of the city, county, and State of New York, and ISAAC OSGOOD, of Utica, in the county of Oneida, and State of New York, have invented certain new and useful Improvements in Apparatus for Dyeing and Bleaching Thread and Yarn; and we do hereby declare that the following is a full and exact description thereof, reference being had to the accompanying drawings, and to the letters of reference thereon.

To enable others skilled in the arts to comprehend, make, and use our invention, we will proceed to describe its nature, construction, and operation.

The nature of our invention consists in forcing dyeing, bleaching, or cleansing-liquids through any fibrous material which has been spun or wound in the form of thread or yarn, upon grooved, fluted, or corrugated bobbins, spools, or cop-tubes, or which has been spun or wound upon a spindle in the form of a cop, and afterwards placed upon a fluted or grooved skewer.

It also consists in fluting, grooving, or corrugating the bodies of bobbins, spools, cop-tubes, or skewers, which are used for dyeing or bleaching, so as to provide passages for dyes or other fluids into or through the yarn, or in fluting or corrugating and perforating the same for the said purpose, and in providing for the bobbins or spools peculiar metallic heads.

It further consists in employing cop-shaped receivers for the lower end of the bobbins, spools, or cops, so constructed as to direct the dye or other liquids into the grooves or corrugations, and through them into the yarn, and in the employment of a peculiar receiver for the upper end of the bobbins, spools, cop-tubes, or cops, which shall serve as a support, and at the same time resist the action of the force-pump to raise the same from the lower receiver.

The term "yarn" used in this specification is intended to include threads or twists of cotton, wool, flax, silk, or other fibrous substances, capable of being spun or wound for use; and we use the term "spool," which has two heads, to distinguish it from a bobbin, which has but one head, and from a cop-tube, which has no head.

Figure 1 is a vertical section of a portion of our improved apparatus, showing a fluted skewer in elevation.

Figure 2 is a vertical section of the same, showing a grooved or corrugated bobbin.

Figure 3 is the same, showing a perforated cop-tube.

Figure 4 is the same, showing a corrugated and perforated bobbin.

Figure 5 is a vertical section of a lower receiver and a bobbin or spool-head, with a rubber packing in the receiver, for the reception of the bobbin or cop, to secure perfect connection.

Figure 6 is a horizontal section of a cop, cop-tube, and a fluted or grooved skewer.

Figure 7 is a bottom view of a lower receiver, showing the lower end of a fluted skewer.

Figure 8 is a view of the lower end of the follower in the upper receiver, showing a rubber packing.

Figure 9 is a horizontal section of a cop-grooved or corrugated bobbin and round skewer.

Figure 10 is a bottom view of a lower receiver, showing openings or passages for fluids up into the yarn.

Figure 11 is a view of the end of a bobbin or spool, showing passages through the head by the corrugations in the body.

a, conducting-pipes, which bring dyes or other fluids from a force-pump; *b*, bosses soldered upon the conducting-pipes, into which the lower receivers, *c*, are screwed; *c'*, openings through the receiver; *d*, grooved or corrugated bobbin, showing perforations; *e*, head of the same; *f*, perforated cop-tube; *g*, fluted or grooved skewer; *g'*, round skewer; *h*, bars which support the upper receivers; *i*, longitudinal grooves or corrugations in the body of the bobbin; *i'*, longitudinal flutes or grooves in the body of the skewer; *k*, upper receiver for a bobbin; *k'*, the same for a cop; *l* and *l'*, enlargements at the lower ends of the same, perforated, to receive and support the yarn; *m*, follower, which is caused by spring *n* to press upon the top of the bobbin; *n'*, spring, which causes receiver *k'* to press upon the yarn; *o*, rubber packing in the lower receiver, to receive the inner cylinder of the bobbin-head; *p* and *p'*, cops shown by dotted lines; *r*, perforations through which the dye passes from the inner to the outer grooves.

Both the body and head of the bobbin *d* are "struck up" out of sheet metal, and, by the grooving or corrugation of the body of the bobbin, passages are formed, both inside and out, as seen at *i*, fig. 9, through which the dye or other liquids may pass into the interior of the yarn. These passages continue through the head of the bobbin or spool, as seen at *i*, fig. 11, and by means of passages *c'* through the lower receiver, are in connection with the conducting-pipe *a*. In forming the head of the bobbin, the metal at the centre is driven down, as seen at *e'*, so as to form a cylinder or band, which is soldered around the corrugated body, thus leaving the passages continuous through the head. The outer portion of the metal is also driven down so as to form the outer cylinder of the head, as seen at fig. 5. The inner cylinder of the head fits into the upper end of the receiver, so that when pressure is applied upon the upper end of the bobbin or yarn, no liquid can escape from the receiver without passing into the grooves or corrugations of the bobbin.

The cop-tube is here represented of the full length of the cop, though they are generally shorter, and in many cases the cop is formed upon a spindle without the use of a cop-tube or bobbin. The cop-tube may be corrugated like the bobbin, and, if long enough, would serve to conduct the liquids into the yarn; but in case the cop is formed without the use of a cop-tube, or when a round, perforated cop-tube is used, we employ a fluted or grooved skewer, as seen in figs. 1, 6, and 7. The fluted skewer is inserted into a round hole in the receiver, and extends through it, so that the flutes or grooves are in direct connection with the conducting-pipes. Through these grooves the dye and other liquids pass up into the interior of the cop of yarn, whether a perforated cop-tube be used or not.

The upper receiver, *k*, is fastened to the bar *h*, and when pressed down the follower rests upon the upper end of the bobbin, closing it by the power of spring *n*, so that no liquids can pass through it, and at the same time holding it against the tendency of the liquids to raise it off the lower receiver. The lower end of the receiver *k* is enlarged to fit the cop, and perforated so that if it rest upon the yarn the dye can escape readily through the perforations. Receiver *k'* has no follower, as no bobbin is employed, but rests entirely upon the yarn or cop, and is thrown down by the power of spring *n'*. These upper receivers should be made adjustable, by means of screw-nuts or otherwise, so as to suit them to long or short cops or bobbins. When no bobbin is used the cup-shaped receiver embraces the lower end of the cop, so as to prevent the liquids from escaping, except through the grooves of the skewer into the yarn.

In using the apparatus herein described, we employ a bath of about twelve inches in depth, and large enough to contain several hundred cops. Across the bottom of this bath we place as many conducting-pipes as are required, all of which are in direct connection with the force-pump. Into these conducting-pipes we insert the lower receivers, at convenient distances from each other, and directly over each conducting-pipe we place a bar, *h*, with its upper receiver corresponding in numbers and position with the lower receivers. These bars may be fastened to the bath by hinges and clasps, or by any other convenient method. Each bath may, if desired, contain both fluted skewers and round ones, for dyeing yarn upon bobbins and without bobbins. There should also be stop-cocks employed in the conducting-pipes, so that the liquids may be shut out of some of them if necessary.

In use we place cops of yarn, with bobbins in them, in the bath, upon the round skewers, and the cops without bobbins upon fluted skewers. The bars are then pressed down and fastened, each upper receiver coming down upon a cop or bobbin, holding it firmly in its place upon the lower receiver. The cops are then ready for scouring, bleaching, or dyeing, as the case may be. The pump should be so arranged that by means of a flexible supply-pipe it may readily be placed in connection with either of the liquids employed. The discharge-pipe from the bath should also be flexible, so that the liquids may be returned to the vessels from which they have been taken by the pump.

When the force-pump is put in operation, the liquid is forced above the conducting-pipes, up through the receivers into the grooves, either in the bobbins or the skewers, through the yarn into the bath, from whence it runs back to the vessel from which it was drawn.

Woollen yarn generally requires to be cleansed before it is dyed. In that case soda-water is first forced through the yarn, then pure water to rinse it, then a mordant to prepare the yarn to receive the dye, then the dye, then water to rinse it, then steam to drive out the water, and lastly hot air, to complete the operation of drying. If at any time during the operation it becomes necessary to air the yarn, a stop-cock may be used in the supply-pipe near the pump for partially or entirely cutting off the supply of liquids, and a pet-cock placed in the supply-pipe between the stop-cock and the pump, may be opened, when air will be drawn into the pump and forced through the yarn.

To adapt this apparatus to dyeing on spools, it might be necessary to employ a pointed follower in the upper receiver, or a follower shaped like the lower receiver might be used. The lower receiver might also require alteration so as to conform to the shape of the spool. The body of the spool may be perforated and employed with a fluted or grooved skewer, or it may be corrugated and employed with a round skewer.

Round and perforated bobbins, spools, and cop-tubes may be employed with square skewers, or skewers not round, but this we consider an equivalent of fluted or grooved skewers. Fluted skewers may also be employed with fluted or corrugated bobbins.

Having described our invention, what we desire to have secured to us by Letters Patent of the United States, is—

1. Grooves, flutes, or corrugations *i* and *i'*, for conducting dye and other liquids to the interior of a cop of yarn, when employed substantially as herein described.
2. The grooved or fluted bobbin *d*, when employed substantially as and for the purpose herein specified.
3. Grooved or fluted skewer *g*, when employed substantially as and for the purpose herein set forth.

4. The cup-shaped receivers *c*, through which the liquids pass from the conducting-pipes to the cops, substantially as specified.
5. The combination of the receiver *c* with the bobbin *d*, when the receiver is made to embrace a portion of the bobbin, substantially as and for the purpose herein specified.
6. The combination of spring *n* and *n'* with the upper receivers, to adjust them to the length of the cop or bobbin, substantially as and for the purposes set forth.
7. The follower *m* and spring *n*, in combination with bobbin *d*, substantially as and for the purposes specified.
8. The combination of an upper adjustable receiver with a lower receiver, when constructed substantially as specified.
9. The employment of a fluted or grooved skewer, in combination with a perforated cop-tube or bobbin, substantially as described.
10. The metallic bobbin or spool-head *e*, when struck up so as to form an inner and outer cylinder, in combination with corrugated or perforated body *d*, substantially as specified.
11. The combination of corrugations and perforations in the same body, substantially as and for the purpose specified.
12. The employment of a skewer for supporting a bobbin, cop-tube, or spool, in combination with the receivers *c*, substantially as and for the purpose herein specified.

ISAAC OSGOOD,
WM. H. ELLIOT.
